PROCESS AND APPARATUS FOR MOLDING
SOAP

Robert Craig, Heswall, and Laurence Seymour Harber, Peterborough, England; said Harber assignor to Baker Perkins Limited, Peterborough, England, and said Craig assignor to Lever Brothers & Unilever Limited, Port Sunlight, England, a company of Great Britain

Application January 25, 1941, Serial No. 375,986
In Great Britain January 26, 1940

16 Claims. (Cl. 25—9)

This invention relates to an improved method and apparatus for molding and cooling molten soap so as to produce small soap billets or cakes of a size and form suitable for the direct stamping of the soap into tablet form.

Methods and apparatus for molding and cooling molten soap into the form of solidified cakes have been heretofore proposed. They comprise broadly the filling of the molten soap into each of a plurality of open molds mounted to move in an endless series past the soap feeding means and then past means for ejecting the soap from the molds, the molds being subjected to the action of a cooling liquid during their passage between the feeding and ejecting means. These heretofore proposed methods and apparatus are, however, associated with many objections among which is the unequal shrinkage of the soap during cooling with consequent distortion of the solidified billets.

One of the objects of the present invention therefore is to provide an improved method and apparatus to reduce or overcome this unequal shrinkage and to produce soap billets having a substantially uniform surface.

Another object of the invention is to provide a method and means to avoid the inclusion of air bubbles in the soap during the filling of a mold.

A further object of the invention is to provide means to facilitate the removal of the soap from the mold without damage to the soap surfaces.

The above and additional objects and features of the invention are accomplished by our improved method and apparatus as described briefly herebelow and in greater detail hereinafter.

The improved method comprises the steps of confining a portion of molten soap to a desired shape, subjecting the soap to pressure and chilling the soap while it is thus subjected to pressure. More particularly, the molten soap is fed under pressure into a mold against means providing a yielding resistance to avoid the inclusion of air bubbles in the soap during the filling of the mold. The filled mold is covered and the soap contained therein subjected to pressure. The mold is then chilled while the soap is thus subjected to pressure and until a thin outer shell of solidified soap is formed in the mold, the thickness of the shell being sufficient to permit the molded soap to be removed from the mold without distortion. The mold is then uncovered and the soap billet ejected and further subjected to a more gradual cooling treatment.

A form of apparatus or machine selected for purposes of illustrating means by which our

method may effectively be carried out comprises an endless conveyor or drum carrying a continuous series of molds each having an open side through which it is filled and an opposite side or bottom formed by a plunger. To avoid the inclusion of air bubbles in the soap the plunger is yieldably urged to a position at the commencement of the filling operation of each mold where it is flush with the open side of the mold so that there is no air present in the mold which can be trapped in the soap. The amount of soap fed into each mold is controlled by a stop limiting the extent to which the plunger can be depressed and preferably this stop is adjustable in position so that the amount fed can be varied.

The open sides of the molds are covered in a progressive manner by means of a continuous band of stainless steel or other flexible non-corrosive material held firmly against and moving with the molds so that the soap is maintained under the pressure exerted by the plungers and at the same time access of air is prevented. In order to prevent displacement of the soap by the plunger during the interval between the filling of the mold and the covering of the open side, the pressure exerted by the plunger is preferably reduced or removed by suitable means during this interval.

The soap in the molds should be cooled as rapidly as possible and this is preferably done by immersing the molds in a cooling liquid such as brine or by spraying the cooling liquid on to the surfaces of the molds and the mold cover or by employing in succession both spraying and immersion.

To remove the billets from the drum a transfer wheel and conveyor arrangement is provided to which the soap billets are discharged from the molds. The transfer wheel receives the billets from the molds and transfers them to a conveyor which is arranged to carry the billets away while they are at the same time subjected to further cooling. The conveyor may be so constructed that the billets are each supported by slats or other suitable supports and are air-cooled to a suitable temperature for stamping, for example a mean temperature of 30° to 35° C.

For a better understanding of the invention reference is made to the following detailed description to be read in connection with the accompanying drawings, in which:

Figure 1 is a diagrammatical illustration of a form of apparatus selected for purposes of illustrating the invention;

Figure 2 is an enlarged view in vertical eleva-

tion with parts broken away showing details of the apparatus; and

Figure 3 is a sectional view of the apparatus taken substantially along lines 3-3 of Figure 2.

As shown diagrammatically in Fig. 1 of the drawings the apparatus selected for purposes of illustrating the invention comprises a rotatable drum 1 supported on trunnions 2 and having a continuous series of molds 3 arranged around its periphery. A nozzle 4 is provided at the filling station for feeding molten soap to the molds and a flexible endless stainless steel metal band 5 is arranged progressively to cover the molds as they leave the filling station and to move with them to a position just short of the discharge station. At the discharge station the soap cakes are pressed out of the molds into pockets in a transfer wheel 6 which carries the cakes to a position indicated at 7 where they are transferred to an upwardly moving conveyor 8.

The drum 1 which is driven by gears 9 comprises a number of sections, as shown in Figs. 2 and 3, each carrying a series of molds at its periphery. The nozzle 4 is hot water jacketed and has an outlet for each section of the drum. The outlets of the nozzle through which the molten soap enters the molds have the same dimensions as the molds. The nozzle facings fit closely around the circumference of the drum and are extended circumferentially so as to closely cover the molds at the filling station. The nozzle facing at the trailing or rear side extends to a knife edge 10 and is shaped to fit to the curvature of the steel band 5 where it passes around a supporting pulley 11. The whole of the nozzle fitting is pivoted about an axis at 12 to enable the nozzle to be moved away from the drum for cleaning purposes.

The bottoms of the molds 3 are in the form of close-fitting plungers or pistons 13 which are urged toward the open side of the molds by springs 14 cooperating with stirrups 15 secured to the drum surface.

In operation the molds approach the filling nozzles with the pistons biased to the top of the molds by the springs 14 and held in that position by a cam 16 engaging the ends of the piston rods 17. As the molds reach the filling station the piston rods 17 move off the cam 16 and the pistons are retained in position by the pressure of the springs 14 until they are forced inwardly by the pressure of the soap entering the molds. The end of the cam 16 has an inclined surface 18 to prevent the instantaneous filling of the molds.

In this way the soap is maintained under pressure during the whole of the filling of the molds which prevents the formation of air bubbles or voids in the soap.

The pistons are pressed inwardly by the soap pressure until the piston rods 17 come into contact with a stop 19. The stop 19 is supported from a fixed portion 20 and its position is adjustable to vary the extent of the movement of the pistons and therefore the amount of soap which is fed into the molds. If desired the means for adjusting this stop may be so arranged that they can be operated while the machine is in operation.

As the molds move away from the filling station transverse pins 21 near the ends of the piston rods 17 move under flanges 22 which prevent the springs 14 from urging the pistons outwardly until the open surfaces of the molds are covered by the stainless steel band 5. The

flanges 22 are supported from the stop 19 so that once set they will always be correctly positioned in relation to the stop for any position of its adjustment.

To enable the machine to be operated without soap pressure (e. g., for trial or cleaning purposes) the flanges 22 are provided with sloping extensions as shown at 23. These extensions are so arranged that if, during the rotation of the drum, the piston rods move off the end of the cam 16 without being depressed by soap pressure the pins 21 will engage under the flanges 22 and be guided downwardly by those flanges until they engage the under surface of the flanges 22.

As soon as the molds are covered by the stainless steel band the piston rods are released from the flanges 22 and the springs 14 tend to push the pistons outwardly thereby applying pressure to the soap against the steel band. To resist this pressure the pulley 11 is pressed against the surface of the drum and the steel band is maintained under tension by a tensioning pulley 21.

Immediately after leaving the filling station the molds are sprayed with jets of cooling liquid issuing from nozzles 28 which effects preliminary cooling of the soap.

This preliminary cooling continues until the molds are immersed in cooling liquid contained in a bath 29. The cooling liquid in the bath, which may be the same as that issuing from the nozzles 28, may be brine and it may be maintained at a low temperature by cooling coils immersed in the liquid or the liquid may be drawn away from the bottom of the tank by a pump and passed through cooling coils back to the nozzles 28 and thence to the body of the liquid in the bath. When brine or similar corrosive cooling liquid is employed, the bath and other parts of the machine which come into contact with the liquid should be made of corrosive-resistant material such as stainless steel or mild steel clad with stainless steel or tin coated cast iron.

The stainless steel band 5 is driven by its engagement with the surface of the drum and it remains in contact with the molds until the latter leave the cooling bath. Immediately before the band leaves the molds by passing around the pulley 30, the pins 21 on the piston rods move under flanges 31 which control the outward movement of the pistons in such manner that the soap is gradually ejected from the molds. The ejection of the soap is effected by the springs 14 in conjunction with a cam bar 32 engaging the ends of the piston rods. The soap cakes 33 as they are ejected are received in pockets in the transfer wheel 6 formed by the fingers 34. The transfer wheel is driven from the drum by means of gears and it has the same peripheral speed as the drum. At a point on the transfer wheel diametrically opposite to that at which the cakes are received, the cakes are pushed out of the pockets by a cantilever pusher rod 35 on the conveyor 8.

The conveyor is of the vertical chain link type and is fitted with rubber covered pins 36, 37 which support the cakes. In order to carry out satisfactorily the transfer operation from the wheel 6 to the conveyor 8 the transfer wheel as a whole is caused to travel in an upward direction at the same speed as the conveyor 8 during the transfer operation by means of a cam 38 engaging a follower 39 on the arm 40 which carries the transfer wheel and which is pivoted at

the centre of rotation of the drum 5. The movements of the arm 40 also effect the movements of the pusher 35. Immediately the cake has been transferred to the conveyor the transfer wheel moves back into its original position. During the time the cakes are on the transfer wheel air is blown on to them from jets 41 which blows away any adherent cooling liquid and effects a further degree of cooling of the soap.

The conveyor 8 may be arranged to pass the cakes to an air conditioning chamber prior to the final stamping operation. Further, the cakes may be subjected to additional cooling by means of an air blast, while they are on the conveyor and the conveyor may be so arranged as to turn the cakes over at regular intervals during the cooling operation in order to make the shrinkage as uniform as possible and to prevent remelting of the soap at points of contact with the pins of the conveyor. The final cooling of the soap may be effected after stamping and, as before, by means of air.

In the operation of the machine a pressure of about 1 lb./sq. in. is used on the soap at the filling nozzles and the temperature of the soap at this point is normally maintained at about 70° C. The temperature is preferably the minimum that will ensure fluidity of the soap in order to reduce as far as possible the tendency of the solidified shell on the tablets to remelt after they have been removed from the cooling liquid. The time of cooling of the soap in the molds is normally about two minutes and brine used has a temperature of about 2° C. These conditions, such as temperature, pressure and time of cooling, may of course, be considerably varied without departing from the spirit of the invention.

The solidified shell of cooled soap formed on the tablets during the cooling in the molds has the form of an outer layer of hard soap merging through layers of soap of increasing softness into the still liquid soap inside the tablet. The thickness of the hard shell formed when the invention is carried out as described in the above example is approximately $\frac{1}{8}$ ". This thickness however varies with the operating conditions.

It will be apparent that by use of the machine herein described molten soap can be confined to a desired shape and subjected to pressure to maintain that shape during the chilling operation and until a solidified shell is formed. The cakes thus formed are removed and carried over a cooling conveyor where they are periodically turned and subjected to cooling air to complete the solidification thereof. During this latter cooling of the cakes the shape of the cakes is maintained without any appreciable uneven shrinkage or the remelting of the solidified shell.

While we have shown and described a particular form of apparatus by which the method can be carried out, it will be readily apparent that other apparatus or that many changes and variations of the apparatus disclosed can be made and used to carry out the method without departing from the spirit of our invention. It will therefore be understood that the form of apparatus herein illustrated and described is intended to be illustrative of the invention only and not as limiting the scope thereof.

We claim:

1. The method of molding molten soap into billets and the like comprising forcing molten soap into a mold, resisting the introduction of the molten soap by a continuously exerted resilient force to avoid the inclusion of air bubbles

in the soap during the filling of the mold, and chilling the mold while the soap therein is maintained under pressure.

2. The method of molding molten soap into billets and the like comprising forcing molten soap into a mold, resisting the introduction of the molten soap by a yielding force to avoid the inclusion of air bubbles in the soap during the filling of the mold, covering the filled mold, subjecting the soap contained therein to resiliently exerted pressure that is substantially the same irrespective of any small changes in volume of the soap in the mold, and chilling the soap while thus subjected to said pressure.

10 15 20 25 30 35 40 45 50 55 60 65 70 75

3. The method of molding molten soap into billets and the like comprising confining a portion of molten soap to a desired shape, subjecting the soap to a continuously exerted resilient pressure to maintain the soap in such shape while solidifying, and chilling the soap while thus confined under said pressure to form at least a solidified outer shell.

4. The method of molding molten soap into billets and the like comprising confining a portion of molten soap to a desired shape, subjecting the soap to a continuously exerted resilient pressure to maintain the soap in such shape while solidifying, chilling the soap while thus subjected to said pressure to form at least a solidified outer shell, removing the confining pressure, and further cooling the soap to complete solidification thereof.

5. Apparatus for molding molten soap into billets and the like comprising a mold, means to feed molten soap into said mold, means to subject the soap contained in the mold to a continuously exerted resilient pressure during cooling, and means to chill the soap while thus subjected to pressure.

6. Apparatus for molding molten soap into billets and the like comprising a mold, means to feed molten soap into said mold, means to cover said mold, means to subject the molten soap confined in the mold to a continuously exerted resilient pressure during cooling, means to cool the soap while thus subjected to pressure to form at least a solidified outer shell, and means to remove the billet of soap from the mold for further cooling.

7. Apparatus for molding molten soap into billets and the like and cooling the same comprising a mold having an open top and a bottom member movable to a position substantially flush with the open top during both a filling of the mold with soap and a subsequent cooling thereof, means yieldingly biasing said bottom member to said position, means to feed molten soap under pressure into said mold against the force of said yieldable biased member, means to cover the top of the mold to confine the molten soap against the pressure exerted by said bottom member, and means to chill the soap while thus subjected to pressure.

8. Apparatus for molding molten soap into billets and the like and cooling the same comprising a mold having an open top and a bottom member movable toward a position substantially flush with the open top during both a filling of the mold with soap and a subsequent cooling thereof, means supplying a force tending to move said bottom member toward said position, a nozzle to feed molten soap, means for moving the mold to bring the open top thereof into position adjacent said nozzle for reception of soap against

the yielding resistance of said bottom member, and means to cover said mold as the mold is moved away from said nozzle.

9. Apparatus for molding molten soap into billets and the like and cooling the same comprising a mold having an open top and a plunger bottom, means to yieldably urge said bottom toward a position substantially flush with said open top during a filling of the mold with soap and a subsequent cooling thereof, means to feed molten soap into said mold against the yielding pressure of said bottom, means to cover the open top of the mold when filled, and means to render ineffective the yielding pressure normally exerted by said plunger bottom during the covering of the mold.

10. Apparatus for molding molten soap into billets and the like comprising an endless conveyor, a series of molds carried by said conveyor, means for filling each of said molds with molten soap, means to cover each mold, means to maintain the soap contained in the mold under a continuously exerted yielding pressure for a predetermined travel of the conveyor, means to chill the filled molds during such travel, means to eject the chilled soap from the molds at the end of said predetermined travel, and means to remove the billets and subject them to further cooling.

11. Apparatus for molding molten soap into billets and the like comprising a mold having an open top and a plunger bottom associated with means to bias it toward a position substantially flush with the open top during a filling of the mold with soap and a subsequent cooling thereof, a nozzle to feed molten soap into the open top of the mold against the yielding resistance of said bottom, means to cover said mold, means to render said biasing means ineffective after the filling operation and until the mold is covered, means to chill the mold, means to uncover the mold after a predetermined chilling, and means to positively move said bottom to eject the soap billet from the mold after the uncovering operation.

12. Apparatus for molding molten soap into billets and the like and cooling the same comprising a rotatable drum, a series of molds arranged at the periphery of the drum and having an outer open side and an inner plunger bottom movable to a position substantially flush with said open side during a filling of the mold with soap and a subsequent chilling thereof, a spring biasing said plunger tending to move it toward said position during both the filling and cooling operation, a nozzle arranged closely adjacent the periphery of said drum to feed molten soap into each mold against the yielding resistance of the plunger bottom thereof, and a continuous flexible member arranged to progressively cover the molds as they move away from said nozzle.

13. Apparatus for molding molten soap into billets and the like and cooling the same comprising a rotatable drum, a series of molds arranged at the periphery of the drum and having an outer open side and an inner plunger bottom movable to a position substantially flush with said open side during a filling of the mold with soap and a subsequent chilling thereof, a spring biasing said plunger tending to move it toward

said position during both the filling and cooling operation, a nozzle arranged closely adjacent the periphery of said drum to feed molten soap into each mold against the yielding resistance of the plunger bottom thereof, a continuous flexible member arranged to progressively cover the molds as they move away from said nozzle, and means for holding said plunger bottom against movement by said spring toward said open side after the filling operation and until the mold has been covered.

14. Apparatus for molding molten soap into billets and the like and cooling the same comprising a rotatable drum, a series of molds arranged at the periphery of the drum and having an outer open side and an inner plunger bottom movable to a position substantially flush with said open side during a filling of the mold with soap and a subsequent chilling thereof, a spring biasing said plunger tending to move it toward said position during both the filling and cooling operation, a nozzle arranged closely adjacent the periphery of said drum to feed molten soap into each mold against the yielding resistance of the plunger bottom thereof, a continuous flexible member arranged to progressively cover the molds as they move away from said nozzle, and means for holding said plunger bottom against movement by said spring toward said open side after the filling operation and until the mold has been covered.

15. Apparatus for molding molten soap into billets and the like comprising means including a series of molds and means to eject the soap billets from said molds when at least partly solidified, a conveyor, and transfer means including a series of pockets adapted to receive the billets as they are ejected and move them to the conveyor, and means to cool and further solidify the billets while they are in said pockets.

16. Apparatus for molding molten soap into billets and the like and cooling the same comprising a rotatable drum, a series of molds arranged at the periphery of the drum and having an outer open side and an inner plunger bottom movable to a position substantially flush with said open side during a filling of the mold with soap and a subsequent chilling thereof, a spring biasing said plunger tending to move it toward said position during both the filling and cooling operation, a nozzle arranged closely adjacent the periphery of said drum to feed molten soap into each mold against the yielding resistance of the plunger bottom thereof, means to progressively cover the molds for a predetermined travel during rotation of the drum, means to render said yielding resistance ineffective during the covering of the mold, means to chill the molds while covered and while the soap therein is subjected to a continuously exerted resilient force, a conveyor, a transfer wheel disposed between said drum and said conveyor having pockets to receive the billets, means to eject the formed billets from said molds, and means for periodically moving said transfer wheel in the direction of drum rotation to receive an ejected billet and deliver a billet previously received to said conveyor.

ROBERT CRAIG.

LAURENCE SEYMOUR HARBER.
